UNITED STATES PATENT OFFICE.

JOSEPH SACHS, OF HARTFORD, CONNECTICUT, ASSIGNOR TO THE SACHS LABORATORIES INCORPORATED, OF HARTFORD, CONNECTICUT, A CORPORATION OF CONNECTICUT.

COUPLING.

1,082,558.

Specification of Letters Patent.

Patented Dec. 30, 1913.

Application filed January 13, 1913. Serial No. 741,745.

To all whom it may concern:

Be it known that I, JOSEPH SACHS, a citizen of the United States, residing at Hartford, in the county of Hartford and State of Connecticut, have invented certain new and useful Improvements in Couplings, of which the following is a specification.

This invention relates to couplings, one of the primary objects of the invention being 10 to provide an article of this character by which a plurality of relatively separable members can be detachably connected and which when in active position effectively maintains said members in proper relation 15 with each other, the construction being such that the coupling can be readily and quickly applied and as easily removed.

At the outset I desire to make it clear that the coupling can be employed with facility 20 in widely-different connections, although it is of peculiar advantage when used in the field of electric lighting, being adapted when utilized in this particular connection for connecting a shade, globe or guard with an 25 incandescent lamp socket, these being merely three of the many examples.

In the drawings accompanying and forming part of the present specification I have shown several of the many different forms 30 of embodiment of the invention which will be set forth in detail in the following description. It will be obvious that I do not restrict myself to this particular disclosure; I may depart therefrom in several respects 35 within the scope of the invention defined by the claims following said description.

Referring to said drawings: Figure 1 is a 40 sectional elevation of a coupling involving my invention, associated with a shade and applied to an incandescent lamp socket, the coupling being in operative position and a part of the shade being broken away. Fig. 45 2 is a transverse section on the line 2—2 of Fig. 1. Fig. 3 is a sectional elevation of said coupling in releasing position, a part of the shade being also represented. Fig. 4 is a view corresponding practically with Fig. 2, of a different and duplex form of coupling and also shows a globe adapted for connection 50 with this type of coupling. Fig. 5 is a transverse section on the line 5—5 of Fig. 4. Fig. 6 is an elevation of portion of a guard equipped with the coupling, the latter being 55 shown in releasing position. Fig. 7 is an elevation of the same guard with the similar

coupling in locked relation, the lower part of the guard being in section to show a catch. Fig. 8 is a sectional detail view of another form of coupling showing the same in connection with a guard and also applied 60 to a socket. Fig. 9 is a side view of the parts shown in Fig. 8, a portion of the head of the guard being broken out.

Like characters refer to like parts throughout the several views, which it will 65 be observed are on different scales.

As already intimated the coupling constituting the subject matter of the present case can be utilized in widely different ways. In the drawings I have shown several of these. 70 This coupling can be used for detachably connecting hose or pipes or for detachably securing a top or cover to a can, bottle or other receptacle, although none of these is illustrated. Said coupling preferably comprises a clamping member and a toggle for locking the clamping member in clamping relation. Both the clamping member and the toggle may vary radically as to character, depending in a measure upon the nature 75 of the members to be separably united. Ordinarily but not necessarily the clamping member consists of a plurality of approximately-circular segments, and these segments will embrace preferably or surround 80 a part such as the socket of an incandescent lamp. When the toggle connected with the clamping member is in operative or closed position, the clamping member will rigidly 85 and firmly embrace the object in question to 90 an extent sufficient to insure against accidental separation of the parts, although the toggle can be unlocked or opened with a comparatively small amount of manual 95 force.

With the foregoing general description, I will now refer first specifically to Figs. 1, 2 and 3, wherein the coupling is shown connected with a lamp shade or reflector such as that denoted in a general way by 2, the 100 socket of well-known construction being designated by 3. The shade 2 has an up-standing neck or collar 4 which is intended to embrace the socket 3 and which as shown, has an interior approximately annular 105 groove or channel 5 to receive the external circular bead or flange 6 of the socket 3 when the shade 2 is properly connected with said socket, which is one simple means for interlocking the socket and clamping mem- 110

ber. The presence of this groove and bead, however, are not matters of consequence, as equivalent means might be substituted therefor or in some cases omitted. The collar or neck 4 is approximately diametrically oppositely slotted as at 7 to form two duplicate segments 8, and this neck or collar 4 I might add constitutes the clamping member of the coupling shown in Figs. 1, 2 and 3. Although this clamping member is shown as an attached part of the shade 2, it may be made separably. The segments 8 of the collar 4 near the body of the shade 2 are slit as at 9 thereby producing in said segments a certain amount of resiliency which can be advantageously utilized for facilitating the connection of the clamping member or collar 4 with the socket 3. Although this resilience is naturally of advantage, it is not always essential that it be present as the clamping members of the other forms of the coupling have not this resiliency or at least not so much thereof.

As already indicated the toggle for locking the clamping member, of whatever character the same may be, to a socket or other part may vary decidedly, although that shown in Figs. 1 to 3 inclusive has met all the conditions. This particular toggle comprises companion toggle members or links 10 and an operating or actuating toggle member 11. As shown the toggle members or links 10 are of yoke or U-form, and although illustrated as semi-circular, this is not a matter of consequence, as they might as well be of some other shape. The inner terminal portions of the branches of the yoke-like toggle members 10 are bent inward as at 12 to present pivots, and extend freely through perforations in the ends of the segments 8 from the outside thereof. The main or actuating toggle element 11 as represented is of annular form, and although circular, this is not imperative, the auxiliary toggle members 10 being preferably pivotally connected with the main toggle member 11 interiorly thereof. For example, I may form in the annular toggle member 11 diametrically opposite ears or lugs 13 through perforations in which the toggle members 10 extend, the connection between said ears and the respective toggle members 10 being approximately midway of the length of the latter.

In Fig. 3, the socket 3 is shown as having been entered into the split collar 4; the bead 6 on said socket being nearly in the channel 5. On the slight farther relative movement of the collar on the socket, said bead will snap into said channel owing to the resiliency of the collar, during which action the segments 8 are slightly spread open, but the instant that the bead is fully seated in the channel, these segments promptly close upon the bead. In this view

the toggle is open or unlocked, the toggle members 10 extending at an upward, outward angle from their point of connection with the inner terminals of said segments, and the toggle member or ring 11 being up. To lock the collar 4 to the socket the ring 11 is moved downwardly thereby correspondingly moving the outer ends of the toggle elements 10, so that the centers of the toggle are caused to approach and then cross the dead center line of said toggle, at which point said toggle will be in locked relation to connect the shade 2 securely to the socket 3, it being understood that when the shade is fastened in place the bead 6 is solidly seated in the channel 5. To release the shade the operation described is reversed. It will be clear that the ring 11 in addition to acting as a member of the duplex toggle also constitutes a facing or finishing ring, inclosing the locking parts and hiding the same from view.

I have thus far described a coupling which is attached to one object and which is adapted to clamp another object by which said two objects can be separably connected together. In Figs. 4 and 5 I show a coupling which has a duplex clamping action being unattached normally to either of the objects to be joined together. When the sections of the clamping member of said duplex coupling are moved into clamping relation by the locking mechanism however, said sections will clamp both the objects, and this effect will be obtained by a single movement of said locking mechanism. In the two views in question the coupling is shown as constructed for connecting a glass globe or shade with a socket, although it might connect any other two parts as already observed. The globe or shade is denoted by 14 and the clamping member is designated in a general way by 15, said clamping member 15 being divided to present sections or segments, the upper portion 15' of each being adapted to coöperate with the socket 16, while the lower portion 15'' thereof is adapted to coact with the globe or shade 14. The upper portion 15' of each of the sections or segments of the duplex clamping member 15 is interiorly channeled to receive the customary bead on the socket 16, while the lower portion 15'' of each of said sections is hook-like or in the form of a claw to engage over the bead at the upper end of the globe or shade 14. The toggle members 17 and the toggle members 18 are exactly like the toggle members 10 and 11 already described in detail, for which reason they require no further specific description. With the toggle (composed of the members 17 and 18, open) as shown in Fig. 4, the socket 16 and shade 14 can both be inserted in the clamping member 15, and when this is done the toggle member 18 will

be drawn downward thereby correspondingly moving the outer portions of the links 17 and causing the sections or segments of the clamping member to approach each other and to clamp against both the shade 14 and the socket 16, it being apparent that when the several centers of the toggle have crossed the dead center line of said toggle, the sections of the clamping member 15 will 10 be firmly clamped to the shade 14 and socket 16, the beads of the two parts at this time snugly fitting grooves or channels within said clamping member. The clamping member 15, therefore, in addition to being 15 clamped to both parts is also interlocked with each, thus insuring double security.

Referring now to Figs. 6 and 7 the numeral 19 denotes an incandescent lamp guard which as shown consists of two like sections. In this showing the head 20 of said guard presents a clamping member, being divided as represented to present duplicate sections or segments connected respectively with the companion sections of the guard. To the sections of said head are pivoted exteriorly the yoke-like toggle links 23 and pivoted centrally to these toggle links is the annular toggle member 24, all like the corresponding parts hereinbefore described. When the double toggle is opened or unlocked as shown in Fig. 6, the sections or segments of the head 20 are spread so as to receive an incandescent lamp socket which, as will be understood, is passed 35 through the ring 24. When this is done, the toggle is moved to locking position to cause the sections or segments of said head to closely embrace the socket of the lamp, the head 20 having an interior channel 25 to 40 receive the usual bead on said socket. The guard 19 may, if desired, be equipped with a latch, that shown consisting of a ring 19' at the lower end of one section adapted to receive the half ring 19'' at the corresponding end of the other section.

In the several forms of the device thus far described, the toggle mechanism is in concentric relation with the clamping member, and the operating element of the toggle mechanism is bodily shiftable, this result being obtained by mounting said operating toggle element for floating movement.

Referring now to Figs. 8 and 9 the guard there shown is denoted by 26 and its head 55 is divided or split to present the segments 27 which jointly constitute a clamping member. To the ends of the segments exteriorly thereof are pivoted two pairs of toggle links 28 which unlike the other links are straight 60 or practically so. To the outer ends of the respective pairs of links 28 are pivoted the ends of operating toggle members 29 equipped with upward extensions 30 projecting through slots in the head of the 65 guard 26 and having bent finger pieces 31

to facilitate their operation. To move the toggle device to unlocked position the finger piece 31 is elevated thereby flexing or opening the two sets of toggles and at the same time separating the segments 27, so that the 70 head of the guard 26 can receive the socket. To lock the guard to the socket the finger pieces 31 are depressed, thereby moving the two toggle devices to locked relation and causing the segments 27 to tightly and 75 firmly embrace the socket.

What I claim is:

1. A coupling comprising a sectional clamping member, and toggle mechanism for applying a clamping force to each section of the clamping member at a plurality 80 of points.

2. A coupling comprising a clamping member consisting of a plurality of segments, and toggle mechanism for applying 85 a clamping force to each segment approximately at its terminals.

3. A coupling member comprising a clamping member consisting of a plurality of yieldingly mounted segments, and a toggle 90 connected with said segments, for locking the same in clamping relation with an object.

4. The combination of a member provided with an annular integral collar divided to 95 form sections, and a toggle connected with said sections, for locking the same in clamped relation with an object.

5. The combination of a member provided with a collar divided to present sections 100 each slit, and a toggle connected with the sections, for locking the same in clamped relation with an object.

6. A coupling comprising a clamping member in sections, toggle members connected with the sections of said clamping member, and an annular toggle member joined to the other toggle members, the several toggle members coöperating to move the sections of said clamping member into 110 clamping relation with an object.

7. A coupling comprising a clamping member in sections, a yoke-like toggle member connected with each section, and an annular toggle member connected with the other 115 toggle members, the several toggle members being coöperative to lock the sections of the clamping member in clamping relation with an object.

8. The combination of a member provided 120 with a collar divided to form clamping segments, yokes, the terminals of which are pivoted to said segments, and a ring inside which said yokes are pivotally connected between their ends, the ring and the yokes constituting a double toggle for locking said 125 segments in clamping engagement with an object.

9. A coupling comprising a clamping member, a ring surrounding the clamping 130

member, and toggle means between the ring and the clamping member, said ring and toggle means coöperating to set the clamping member.

5 10. The combination with an object having a projecting bead on its outer surface, of a coupling comprising a clamping member provided with an annular internal groove engaging with said bead, toggle means connected with said clamping member, and a toggle operating member connected with said toggle means.

10 11. The combination with a lamp socket, an object to be held to said socket, and a coupling for securing and holding said object to said socket, said coupling consisting of a sectional clamping member, and a toggle for locking the sections of said clamping member in clamping relation to said socket.

20 12. The combination with a lamp socket, of a reflector, a coupling attached to said reflector, comprising a clamping member in sections, and toggle means for applying a force to each section of the clamping member at a plurality of points to lock said clamping member in clamping relation to the socket.

25 13. The combination with a lamp socket, of an object to be held thereto, a coupling attached to said object, said coupling comprising a clamping member in sections, and toggle means for applying a locking force to said sections at substantially diametrically opposite pairs of points to move the sections of the clamping member into clamping relation with the socket.

30 14. A coupling comprising a clamping member consisting of a pair of substantially semi-circular segments, and a toggle for applying force to each of the segments at a plurality of points to move said segments together to clamp an object.

35 15. A reflector provided with a coupling for securing it to an object, comprising a yieldable clamping portion, and a toggle connected with said clamping portion, for

50 applying a clamping force thereto at a plurality of different points to move the same into clamping relation with the object to which the reflector is to be secured.

55 16. A reflector provided with a coupling comprising a movable clamping member in sections, toggle means connected with each section of said movable clamping member at a plurality of points, and toggle operating means attached to aforesaid toggle means and by the operation of which the movable member is moved into clamping relation with an object to which the reflector is to be secured.

60 17. In a coupling, a clamping member comprising a plurality of sections, a toggle link connected with each of said sections, and a toggle operating member connected to said toggle links, shaped to inclose the 65 toggle links when in its operative position.

65 18. A coupling comprising a plurality of sections, and toggle locking means for said sections comprising link members, and an operating member for said link members 70 movable relatively thereto, the link members being individually connected with the respective sections.

70 19. A coupling comprising a sectional clamping member, and a toggle locking mechanism for said clamping member comprising an operating toggle member, and a plurality of separate toggle members each of which is connected with said operating toggle member and with its individual section of the clamping member.

75 20. The combination of a clamp, and toggle mechanism for operating the clamp comprising a bodily shiftable annular toggle member.

80 85 In testimony whereof I affix my signature in presence of two witnesses.

JOSEPH SACHS.
